[57] CLAIM

The ornamental design for a well for a soap dispenser, as shown and described.

DESCRIPTION

FIG. 1 is a cross section view of a well for a soap dispenser showing my new design, taken along line 1—1 of FIG. 3;

FIG. 2 is a side elevational view thereof;

FIG. 3 is a top plan view thereof;

FIG. 4 is a bottom plan view thereof;

FIG. 5 is a top plan view of a second modified embodiment, shown in an alternate position;

FIG. 6 is a top plan view of a third modified embodiment;

FIG. 7 is a top plan view of a fourth modified embodiment shown in an alternate position; and,

FIG. 8 is a top plan view of a fifth modified embodiment, shown in an alternate position.

FIG. 1

FIG. 2

FIG. 3

FIG. 4

FIG. 5

FIG. 6

FIG. 7

FIG. 8
